UNITED STATES PATENT OFFICE

2,083,397

INTERNAL-COMBUSTION ENGINE

Alfred Renner, Berlin-Tegel, Germany, assignor
to General Electric Company, a corporation of
New York

Original application January 9, 1933, Serial No.
650,898. Divided and this application Sep-
tember 29, 1934, Serial No. 746,239. In Ger-
many January 11, 1932

1 Claim. (Cl. 60—16)

The present application is a division of my application Serial No. 650,898, filed on January 9, 1933, relating to internal combustion engines, more particularly to the type of engine which is started by means of compressed air supplied to the cylinders during the starting operation.

The general object of the invention is to provide an improved construction and arrangement of this type of engine.

One object of the invention is to provide an improved construction and arrangement for the mechanism operating the starting valve or valves, whereby the length of the cam shaft is reduced.

For a consideration of what I believe to be novel and my invention, attention is directed to the following description and the claim appended thereto in connection with the accompanying drawing.

The single figure of the drawing illustrates a sectional view, partly broken away, of an internal combustion engine embodying my invention.

The engine comprises a cylinder 10 having a piston 11 with a connecting rod 12 connected to a crank shaft in the usual manner, not shown. The piston wall is surrounded by a cylinder liner or casing 13 which together with the wall defines a cooling space 14 through which cooling medium, for instance, water, is circulated. The cylinder has a head 15 defining passages or channels for a fuel inlet valve 16, a starting valve 17 and an outlet or exhaust valve, not shown. The head also defines a cooling chamber 18 surrounding the different valves and communicating with the space 14 between the cylinder and the cylinder liner through a conduit 19 connecting the two chambers or spaces in series. A cooling medium such as water is conducted to the head through a conduit 20 and discharges from the liner through a conduit 21. Fuel is supplied to the engine by means of a fuel pump 22. The pump piston or push rod of the fuel pump has an extension 23 sliding in a guide 23a, and carrying at its lower end a roller 24. The latter is engaged by a cam 25 fastened to a cam shaft or holder 26. During operation the cam surface of the fuel cam 25 forces the roller 24 and accordingly the piston or control member of the fuel pump 22 upward to compress fuel to be supplied to the engine. The fuel discharge of the pump is connected to the valve 16 by a conduit 27. Adjacent the cam 25 is another cam 28 to be brought into engagement with the roller 24 for reversing the engine. In other words, while the engine is running in one direction, for instance, forward direction, cam 25 engages the roller 24, whereas while the engine is running in reversed direction the roller 24 en-

gages the cam 28. The cams 25 and 28 therefore may be termed forward and reversing cams respectively. Other cams fastened on the shaft 26 serve for operating a roller held on a push rod or control member 39 for operating an air inlet valve 40. The upper end of the push rod 39 is pivoted to a lever 41, fulcrumed on a shaft 42. Fastened to the left-hand end of lever 41 is a pin 43 biased in upward direction by a spring 44. During operation the push rod 39 is moved up and down whereby the left-hand end of the lever 41 causes the valve 40 to be opened and closed alternately.

The mechanism so far described is typical of any kind of combustion engine having a cam shaft provided with cams for operating the different valves of the engine for both directions of rotation.

An important feature of my invention is the provision of a starting valve mechanism for conducting compressed air to the engine cylinders to start the engine, which mechanism is directly operated from the piston of the fuel pump. The starting valve 17 comprises a valve casing 56 and a valve member 57. The casing 56 defines a channel 58 to which compressed air may be conducted through a conduit 59. Provided in the valve casing and slidably arranged on the stem 60 of the valve member 57 is a piston 61 biased in downward direction by a spring 62. The upper end of the stem 60 bears against the left-hand end of a lever 64 having an adjustable fulcrum at 65 and being pivoted at 66 to a push rod 67. Such arrangement is more fully disclosed in the patent to Renner, No. 1,925,003, issued August 29, 1933. Connected to the piston 61 by means of a pin 68 is a bell crank lever 69 which has its other end connected to the pivot 65 and is fulcrumed on the shaft 42.

The starting arrangement so far described is more fully disclosed in my United States Patent No. 1,925,003, issued August 29, 1933. Broadly it represents an arrangement for putting the starting valve operating mechanism into an operative position under action of the compressed air supplied to the channel 60. Whereas heretofore this mechanism has been operated directly from a special starting cam on the cam shaft, I provide in accordance with my invention an arrangement whereby this mechanism is operated from the control member for the fuel pump or one of the valves for the cylinder. In the embodiment shown in the drawing the lower end of push rod 67 is pivoted to a lever 70, turning on a shaft 71 and having one end 72 projecting into an opening

or recess 73 in the piston or control member of the fuel pump. The right-hand end of the lever 70 is biased in upward direction by means of a spring 74, to the effect that during normal operation the right-hand end 72 of the lever 70 is out of reach of the fuel pump piston or control member 23. The starting valve mechanism is shown during the starting operation, that is, it is assumed that compressed air is supplied through 10 the conduit 59 to the channel 58 and causes the piston 61 to move upward against the biasing force of the spring 62. This movement effects a turning movement of the bell crank lever 69 in clockwise direction, to the effect that the adjustable fulcrum 65 is moved to a position in which the push rod 67 is lowered so that the right-hand end 15 72 of lever 70 is engaged during the upward movement of the piston 23.

For starting the engine, compressed air is conducted through conduit 59 by opening a valve 17, in the present instance shown as a butterfly valve in the conduit 59. The compressed air flows into the valve chamber 17 and forces the piston 61 upward against the biasing force of the spring 62. During operation, fluid pressure, acting on the lower surface of the piston 61, forces this piston upwardly, compressing spring 62, which spring, acting on the valve stem, maintains the valve closed. The piston 61 being of greater area 30 than the valve 57, maintains the valve closed. When the rod 67 is raised by the cam 28, the valve is positively forced down and opened. The upward motion of the rod 67 also tends to cause a counter-clockwise rotation of the lever 69, 35 which lowers the piston 61 and thus releases the compression of the spring 62, enabling the valve 57 to open. To effect this operation it is necessary that the fuel cam 25 be positioned with its valve opening surface adjacent the roller 24. In 40 a single cylinder engine this may be accomplished manually by turning the cam shaft 26. In a multi-cylinder engine, such as a six-cylinder en-

gine for which the arrangement is primarily intended, such positioning of the cam shaft 26 is not necessary because there will be always one or two cams in a position with their valve opening surfaces engaging the rollers 24. The flow of compressed air into the cylinder forces the piston downward causing turning of the crank shaft which in known manner effects turning of the cam shaft 26. This operation is continued until the speed of the engine has reached a certain value at which combustible fuel is admitted to the engine by any known arrangement (not shown) and the supply of compressed air through conduit 59 is shut off by closing the butterfly valve 17.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by Letters Patent of the United States, is:

An internal combustion engine including a cylinder surrounded by a casing, a cam shaft, a fuel pump having a piston operated by the cam shaft, and means for starting the engine comprising a starting valve cooperating with an opening in the cylinder, means including a channel and a butterfly valve therein for conducting compressed air to the starting valve, means for operating the starting valve directly from the pump piston comprising a lever having one end fulcrumed and another end projecting into a recess in the pump piston and being normally out of engagement with the wall defining the recess and means responsive to the compressed air flowing past said butterfly valve in said channel for automatically effecting movement of said lever so as to engage the wall of the recess and to be reciprocated by the pump piston.

ALFRED RENNER.
